HEAD COVERING

Frances B. Kiffin, Manhasset, N. Y.

Application July 17, 1934, Serial No. 735,577

3 Claims. (Cl. 2-68)

This invention relates to water-proof head coverings and more particularly to a hat or cap designed to protect waved or marcelled hair from wetting or dampness, as, for example, while the wearer is taking a shower or other bath.

One of the objects of this invention is to produce a head-covering, preferably formed of light, water-proof material, such as oiled silk, which will have a preformed crown portion provided 10 with a slit extending inwardly from the base toward the top of the crown portion, and which can be opened and closed and fastened to enable putting on and removal of the hat readily and quickly, and with great ease and facility and without in 15 any way disturbing the hair of the user, and which will also effectually perform its principal function of protecting waved or marcelled hair during a shower bath, a tub bath or during exposure to rain or other moisture.

Still another object of my invention is to provide a hat of the type specified with a slotted crown adjustable to any size of head, which may be securely and firmly fastened on the head without the use of a chin-strap, hat-pins or the 25 like, and which is capable of providing room or space for a knot or knots of long hair at any position on or adjacent to the head.

Still another object of this invention is to provide a hat of the type under consideration with a 30 water-shedding brim adapted in turned-down position to protect the front and sides of the face, ears and nape of the neck and thus avoid wetting of short locks of hair and stray curls, and to shed water outwardly, thus keeping the same 35 away from the eyes, face and neck, whereby the user may be enabled to take a shower bath without removing cosmetics or powder from the face and thus without disturbance of the appearance.

Still another object of my invention is to provide a hat which may be made of oiled silk, light 40 rubber or other water-resistant material of any desired color and which may be folded flat and small enough to be carried in a lady's purse of 45 ordinary size.

Still another object of my invention is to provide a hat of the type specified which will be so 50 neat in appearance and becoming and light in weight that it may be worn while performing household duties such as laundering or cooking to prevent steam from dampening the hair, and may also be worn while performing other household 55 duties as well as outdoors while gardening, boating, fishing or wherever the hair needs protection from dampness, wind and dust and where-ever

the eyes need protection from the direct glare of the sun.

With these and other objects in view the invention comprises the combination of members and arrangement of parts so combined as to co-act 5 and co-operate with each other in the performance of the functions and the accomplishment of the results herein contemplated, and comprises in its adaptations the species or preferred forms illustrated in the accompanying drawing, in 10 which:—

Fig. 1 is a view from the rear and side of a hat embodying my invention, in place on the head of the wearer and showing the brim turned down; 15

Fig. 2 is a front and side view showing the hat embodying my invention in place on the head with the brim turned up;

Fig. 3 is a view in plan of a sheet or blank of material from which the crown portion of my hat is made;

Fig. 4 is a similar view of a blank for the brim which is applied to said crown portion;

Fig. 5 is an interior or bottom view of my said hat, the same being opened to its fullest extent;

Fig. 6 is a top or plan view of the hat shown in 25 Fig. 5 with the flaps partially drawn together;

Fig. 7 is a view in front elevation of my said hat, and

Fig. 8 is a rear view of a slightly modified form of my invention in which the strings or ribbons 30 are replaced by adjustable fasteners.

Referring now to the drawing, my improved hat is preferably formed from a single flat blank or sheet 1 of water-proof material and preferably of oiled silk. The blank 1, as illustrated, is partially circular in conformation with an arcuate edge 1' comprising a major arc or circumference and having an angular slit-forming part comprising equi-lateral rectilinear edge portions extending in a substantially radial direction and 40 meeting at a point near the center of the circle of which the aforesaid major arc forms part, the arrangement being such that when these two rectilinear edges are brought together and overlapped, an initial cone-shaped crown is produced. The apex portion of such an initial crown is then folded flat as at 2, preferably at the inside of the hat, this folded portion which is substantially triangular in conformation is sewed to the adjacent crown portion, thus reducing the cone to 45 a frustro-conic conformation, the top part of which forms the conic surface section 5 in the crown of the finished hat.

The provision below portion 2 of another triangular shaped seam 3^b enables the retention of 55

the overlapped edges in overlapped position and will permit the opening of such overlapping edges to widen the base portion of the initial crown thus formed.

- 5 In the preferred embodiment of my invention the base section 5' of the crown of the hat is provided with a series of pleats 4 suitably disposed around the circumferential edge 1 to produce a better crown formation. The pleats 4 will reduce 10 the diameter of the base portion and will provide a series of overlaps or tucks 4' sewed only at their base portions and the upper loose portions of which merge with the partial conical surface 5. The base of the crown portion is thus 15 reduced and the unsewed upper portions of the pleats provide fullness in the crown, the said pleats, conical surface, and turned down apex portion forming a crown for the hat and said crown has at one edge thereof a slit 3 adapted 20 to be swung open and in open position to provide a crown which is partially convex and partially flat as shown in Fig. 5, thus enabling a ready application of the same to the head without marring the coiffure of the wearer.

- 25 In the preferred embodiment of my invention the arcuate base edge 1' has secured thereto a brim 6. This brim may be secured and the bottom edge of the pleats may be sewed together with a single line of stitching 7.

- 30 The said brim 6 is, as illustrated in Figs. 1 and 2, capable of being turned down to shed water from the eyes and face of the wearer when the hat is used as in a shower or in rain and may also serve to protect the eyes from sun glare. The brim 35 may be turned up, as shown in Fig. 2, when it is desired to wear the hat in circumstances where the water-shedding brim is unnecessary.

- Suitable means is provided for manipulating the edges of the slit 3, and, as illustrated, I provide, as shown in Figs. 5 and 6, ribbons 8 and 9, one of which is attached at 8' to one edge of the slit of outer flap 3^a and the other is attached at 9' to the opposite edge of said slit or inner flap 3'. The ribbon 9 as shown preferably extends beneath the outer flap 3^a and passes through an aperture 9^a at one side of said outer flap, while the other ribbon 8 is adapted to pass directly around the base of the hat when on the head and the ends of the two ribbons are adapted, as 50 shown in Fig. 2, to provide a bow 10 over the forehead of the wearer.

- In Fig. 8 I have shown a modified form of my invention which is in all respects similar to that shown in Figs. 1 to 7 except that the ribbons 8 and 9 are omitted and replaced by providing the external surface of the inner flap 3' with a series of fastener members 11 and the internal surface of the outer flap 3^a with a series of fastener members 11' adapted to cooperate with the members 11 on the inner flap so as to enable adjustment of the flaps for different sizes of heads and/or for the purpose of compensating for knots, rolls or coils of hair.

- Obviously, the slit 3 may be formed at any 65 suitable position along the crown of the hat, as for example, at either side of the hat instead of the back, the specific position of the slit being immaterial so long as it provides a crown portion capable of being opened widely to permit 70 ready application to the head as well as providing adjustment for different sizes of heads. Also, any desirable fastening for the flaps may be employed, which will close the slit and prevent entrance of water therethrough during the taking 75 of a shower or in rain.

It will be seen that the user of a hat of the type under consideration will be enabled to take a shower bath in pleasurable comfort without marring the appearance of the hair; that the hat may be adjusted and applied without the necessity of having to stretch the material in such a way as to rumple the hair; also that the hat when made of oiled silk will avoid the perspiration usually induced when the ordinary rubber cap is employed in a hot-water shower 10 bath; that my improved hat with its openable and closeable crown, when made of light material may be worn with any degree of snugness that the wearer wishes, and in view of the fact that it opens to almost flat condition, it may be 15 lifted off and put on without difficulty and without affecting the curls, marcel or wave of the hair. The hat is simple in construction. The crown may be made from a single piece of material, or, if economy of material is desired, may 20 be cut in two pieces or more. The brim may be sewed or joined in one operation with the ribbons or tie strips, or with re-enforced stay pieces 12 which are fastened under snappers for extra strength. The pleats 4 used in the crown are 25 preferably folded towards the back to more effectively shed water and are left unconnected at the top to insure a comfortable fullness and to raise the hat far enough off the hair to relieve the wearer of any feeling of weight, pulling 30 or restriction. The overlap at the slit is preferably deep, is folded inside, and held in place with said triangular seam of stitching, which also strengthens the portion of the hat where the greatest volume of water is apt to strike it. 35 By leaving the surplus material in the hat, it weighs slightly more and this excess material will tend to keep the hat in place should it be worn while fastened loosely. Said deep overlap also insures that the inner flap will stay in place, 40 thus making it definitely impossible for water to enter through the slit or opening, unless the hat is immersed in a body of water.

Having described my invention, I claim:

1. A head covering comprising a crown portion composed of a piece of sheet material of arcuate configuration having a substantially sector-shaped opening adapted to form an initial cone and a slit, said sheet having at its arcuate edge a series of permanently-fastened plaits 50 to convert the conical base portion into a head-contacting band having substantially the conformation of a cylindrical surface, the material at the apex of said initial cone adjacent to said opening and the top portion of the edges of said 55 sector-shaped opening being folded and fastened to provide a slit having a lapping edge portion and a folded top portion of substantially convex form, said slit extending upwardly through and above said head-contacting band part toward 60 the top of said crown portion and being expandable to fit heads of varying sizes, and means for fastening the edges of said slit in varying closed positions.

2. A head covering comprising a crown portion composed of a piece of sheet material of arcuate configuration having a substantially sector-shaped opening adapted to form an initial cone and a slit, said sheet having at its arcuate edge a series of permanently-fastened plaits to 70 convert the conical base portion into a head-contacting band having substantially the conformation of a cylindrical surface, the material at the apex of said initial cone adjacent to said opening and the top portion of the edges of said 75

sector-shaped opening being folded and fastened to provide a slit having a lapping edge portion and a folded top portion of substantially convex form, said slit extending upwardly through and 5 above said head-contacting band part toward the top of said crown portion and being expandable to fit heads of varying sizes, a brim connected to said vertically-disposed head contacting band of said crown portion and means for 10 fastening the edges of said slit in varying closed positions.

3. A head covering comprising a crown portion composed of a piece of sheet material of arcuate configuration having a substantially sector-shaped opening adapted to form an initial cone 15 and a slit, said sheet having at its arcuate edge

a series of permanently-fastened plaits to convert the conical base portion into a head-contacting band having substantially the conformation of a cylindrical surface, the material at the apex of said initial cone adjacent to said opening and the top portion of the edges of said sector-shaped opening being folded and fastened to provide a slit having a lapping edge portion and a folded top portion of substantially convex form, said slit extending upwardly through and 10 above said head-contacting band part toward the top of said crown portion and being expandable to fit heads of varying sizes and ribbons connected to the opposite edges of said slit to fasten the same together in varying closed positions. 15
